STOCKING

Ralph E. Thompson, Brookline, Mass., assignor to
 Scott & Williams, Incorporated, Laconia, N. H.,
 a corporation of Massachusetts

Application May 5, 1949, Serial No. 91,497

3 Claims. (Cl. 66—180)

1

This invention relates to stockings and has more particular reference to the provision of attractive clocks at the rear of stockings of sheer, seamless type.

The popularity of full-fashioned stockings having seams extending along the back thereof has rather generally caused manufacturers of seamless stockings to provide at the backs of such stockings mock seams. When the stockings are properly adjusted on the legs the seams of full-fashioned stockings and the mock seams of seamless stockings produce an attractive and acceptable appearance by relieving the roundness at the back of the leg and providing a line tending to accentuate straightness of the leg and slimness of the ankles. However, such a long seam or mock seam has the great disadvantage of becoming very unsightly whenever the stocking becomes twisted on the leg, a situation which can be avoided only with the exercise of considerable care. The mock seam in seamless stockings is, furthermore, undesirable in limiting lengthwise extension of the stocking preventing the stocking from being properly drawn up so as to fit neatly around the ankle.

In accordance with the present invention there is provided at the rear of a stocking extending from the ankle to a point thereabove a relatively short reinforced vertical line with appropriate termination at its upper end. This maintains the advantages of the mock seam but with elimination of its disadvantages. This reinforcement, which may be referred to as a clock in view of its general similarity to clocks provided at the sides of stockings, relieves the roundness of the back of the leg, provides a line accentuating the impression of straightness of the leg, and gives rise to an impression of slimness of the ankles. Desirably, this clock terminates short of the hem of a skirt of normal length and has its top end accentuated and limited by a wider portion which most desirably is in the nature of one or more arrowheads or similar vertically elongated areas. Because of its relatively short length twisting of the stocking on the leg tends to create no discernible deviation of the clock from extension along the leg unless such twisting is quite excessive and abnormal.

The general object of the present invention has to do with the provision of such a clock or ornamental stripe and this and other objects relating particularly to details and dimensions will become apparent from the following description read in conjunction with the accompanying drawing in which:

2

Figure 1 is an elevation showing stockings embodying the clocks on a wearer and illustrating particularly the relations between the clocks and the skirt and shoes;

5 Figure 2 is a fragmentary enlarged diagram showing the stitch arrangement involved at the junction of the arrowhead with the stem of the clock; and

10 Figures 3, 4 and 5 are perspective views illustrating various types of clocks which may be provided in accordance with the invention.

Referring first to Figure 1, there are illustrated therein at **4** sheer, seamless stockings, desirably of nylon, and which, except for the clocks which will be described in greater detail, may be entirely conventional. Such stockings, for example, are presently commonly made on machines having, for example, 400 needles, and may have their legs plain knit or knit in special fashions, 15 for example, in accordance with the disclosures of the patent to Albert E. Page, Number 2,501,353, dated March 21, 1950, and the application of Frank R. Page, Serial No. 50,554, filed September 22, 1948. The welts, heels and toes of the stockings may be conventional, the heels being either 20 low or provided with reinforcements in the form of high splices.

In accordance with the present invention such stockings are provided with clocks which, as illustrated in Figure 1, comprise stem portions **2**, arrowheads **6**, and base portions **8**, the latter of which may be so formed of added yarn as to provide upward continuations of the heels or the high splices above the heels. The stem of the 25 clock may extend through the base and the high splice. Desirably the clocks are formed of yarns of such weight as to give an appearance of the same density as, or preferably a greater density than, the reinforced areas of the heels. The 30 most attractive results are secured if the clocks are of such heavy yarn as to stand out in sharp and very definite contrast with the adjacent areas of the sheer leg fabric. As an example, good results are obtained if the clock is formed of 40 or 60 denier yarn in a 15 denier stocking having a reinforcing yarn of 15 denier added in the high 35 splice and heel.

Desirably the clocks should terminate below the hem of the skirt and desirably about $\frac{1}{2}$ inch below the hem of the longest skirt which is worn. With skirt lengths of the present day this means that the clocks should extend upwardly about 7 to 8 inches from the bottom of the heel of the wearer when worn or, considering heels of the 45 stockings, the tops of which generally come about

1 to $1\frac{1}{4}$ inches above the bottom of the heel, the clocks should extend from about $5\frac{3}{4}$ inches to 7 inches above the heel of the stocking when worn. With the stockings off the leg, of course, there is a somewhat greater extension of the clock to the extent of 1 to $1\frac{1}{2}$ inches more. As will be evident, the desirable length of the clock will vary with styles and it will be appreciated that as styles in dress lengths change variations of clock lengths may be made accordingly. As indicated, they should, in general, terminate substantially below the hem of the skirt so as not to have their upper ends cut off from sight when a flaring skirt is viewed looking downwardly at a reasonable distance from the wearer. They should terminate in the vicinity of the lower part of the calf of the stocking, preferably no higher than its lower end.

The stems, such as 2, of the clocks may vary in width and it has been found that a stem three wales wide is quite effective and attractive. The stems, however, may be thicker, for example, up to a width of as much as $\frac{1}{4}$ inch. They may also be as thin as a single wale.

The arrowheads or other widened terminating structures may vary considerably, for example, through a range of 9 to 17 wales in width. Generally speaking, the best appearances are secured if the termination is in the form of one or more vertically elongated arrowheads, diamonds or the like.

If a base 8 is provided this may have an overall width running upwardly from the ranges of width given for the arrowheads. This base may be omitted altogether or may be constituted by the ordinary tapered or untapered high splice.

The clock may be produced by wrapping in various ways well known in the art. A wrap yarn may be provided to form the clock from a wrap finger capable of producing panel wrapping in the usual fashion. Alternatively, the clocking yarn may be provided from an auxiliary finger located at the main feed, being taken only by needles which are selectively raised thereat under the control of pattern mechanism which will determine the needles raised and hence the width of the wrapped panel. The floats, such as indicated at 10 in Figure 2, may be permitted to remain, as they would generally in the narrow portions of the clock, but they may be cut out where they occur across the wider portions of the clocks, such as arrowheads, or the like. Generally, however, they will be sufficiently short as not to require removal.

Figures 3, 4 and 5 show examples of various alternative forms of clocks. In Figure 3 the stem 14 of a clock in stocking 12 is surmounted by an arrowhead 16 and is joined to the reinforcement of the heel through a base indicated at 18. This figure illustrates the relationship of the clock to the hemline of a relatively long skirt.

In Figure 4 a clock of stocking 22 comprises a stem 24 surmounted by a pair of arrowheads 26 with the inclusion on the stem of a diamond enlargement 28. In this case the stem extends through a high splice indicated at 30 forming an upward continuation of the heel reinforcement 32. Figure 4 shows a skirt of intermediate length.

In Figure 5 the stocking 34 carries a clock having a stem 36, upper arrowhead 38 and lower arrowhead 40 which is spaced at 42 from the heel

44. If such an arrangement is used the arrowhead 40 should, of course, terminate above the normal upper edge of the shoe. In the cases previously considered it is desirable that the enlarged base at the bottom of the arrowhead should extend above the shoe edge. However, this is not necessarily the case and the narrow stem itself may well project alone from the upper edge of the shoe. Figure 5 shows a relatively short skirt and, of course, in stockings designed for such skirt length the clock may be carried further upward than illustrated. Desirably, however, the upper end of the clock terminates not substantially higher than the point where the calf bulges above the ankle.

In all of the cases illustrated, which will readily suggest more or less elaborate modifications of the appearance of the clock, the objectives of the invention are attained as set forth above.

What is claimed is:

1. A sheer stocking of seamless type having a clock formed by the inclusion of a yarn substantially heavier than the leg yarn in stitches of the leg, said clock extending upwardly through the central portion of the back of the stocking from a point adjacent to the heel to terminate at a point in the vicinity of the lower part of the calf, said clock through the major portion of its length comprising a narrow, straight stem of not more than one-quarter inch width.

2. A sheer stocking of seamless type having a clock formed by the inclusion of a yarn substantially heavier than the leg yarn in stitches of the leg, said clock extending upwardly through the central portion of the back of the stocking from a point adjacent to the heel to terminate at a point in the vicinity of the lower part of the calf, said clock through the major portion of its length comprising a narrow, straight stem of not more than one-quarter inch width having an enlargement in the upper end thereof.

3. A sheer stocking of seamless type having a clock formed by the inclusion of a yarn substantially heavier than the leg yarn in stitches of the leg, said clock extending upwardly through the central portion of the back of the stocking from a point adjacent to the heel to terminate at a point in the vicinity of the lower part of the calf, said clock through the major portion of its length comprising a narrow, straight stem approximately three wales wide.
